Inventor:

Daniel W. Troy

UNITED STATES PATENT OFFICE.

DANIEL W. TROY, OF MONTGOMERY, ALABAMA.

BOILING-INDICATOR FOR RADIATORS.

1,181,700.

Specification of Letters Patent.

Patented May 2, 1916.

Application filed May 5, 1915. Serial No. 25,977.

To all whom it may concern:

Be it known that I, DANIEL W. TROY, a citizen of the United States, residing in the city and county of Montgomery, State of Alabama, have invented certain new and useful Improvements in Boiling-Indicators for Radiators, of which this is a specification, reference being had to the accompanying drawing, forming part hereof.

10 The invention relates to apparatus intended to prevent over-heating of radiators of internal combustion engines of the water-cooled type, and the object is to provide a simple, inexpensive and efficient device to indicate to the driver when the water in the radiator of his automobile has reached boiling point, or, within certain limits, other temperatures not far removed therefrom.

15 The drawing shows all of the elements of the invention.

On a small spindle or shaft, 1, 1, 1, of some suitable metal, brass, aluminum, or the like (preferably non-corrosive) is fixed a fly 2, shown as a simple two-bladed member 20 having a general reverse curve formation so as to present to the observer from practically any position a concave and a convex face. Any type of fly, however, may be employed; that used on anemometers being 25 typical. Shaft 1 is held loosely in a small tube 3, closed at its lower end and having its upper portion threaded for two nuts, 4, 4. In the lower part of the tube 3 and filling the space between its walls and spindle 30 1 is a fusible material 5, preferably one of the alloys having a melting point around 212 degrees Fahrenheit or slightly below. In use the apparatus is installed on the usual radiator cap, it being necessary only to drill 35 a hole through the cap and secure the tube 3 by the two nuts, one above and one below the cap, as shown, the fly being entirely above the cap and exposed to the air and the lower end of tube 3 being within the radio-

45 tor where it can be reached by steam. The operation is doubtless obvious. At normal 50 temperatures the spindle 1 is locked by the mass of fusible material and cannot rotate notwithstanding the tendency of the fly as the automobile is driven along. Whenever 55 the temperature within the radiator is sufficiently high to fuse the material 5 the spindle can rotate freely and thus indicate the fact of excessive temperature. No indication is given when the automobile is standing, nor is it required under normal conditions.

I prefer to employ as the fusible material one of the alloys melting at or near the boiling point of water, and as only a small quantity is employed the spindle is freed very soon after steam is generated. Obviously if desired the lower end of the spindle may be flattened or roughened but this will not ordinarily be necessary as the alloy will bind it 60 sufficiently against the small torque produced by the exposed fly.

Having described my invention, what I claim is:

1. In apparatus of the class described, a 70 material fusible near the boiling point of water and exposed to the heat of a radiator, a spindle normally held inoperative by said fusible material, and a wind wheel fixed on said spindle.

2. In apparatus of the class described, a tube arranged to be partly inserted in a radiator, a material fusible near the boiling point of water in said tube, a spindle normally held inoperative by said fusible material, and a windwheel on said spindle.

In witness whereof, I have hereunto set my hand, this 3rd day of May, 1915.

DANIEL W. TROY.

In the presence of—

FANNIE KATE CENTERFELT,
THOMAS J. SCOTT.
